United States Patent Office.

JOHN W. BLAKE, OF JEFFERSON, WISCONSIN, ASSIGNOR TO HIMSELF AND
AMAZIAH T. HOWES, OF SAME PLACE.

Letters Patent No. 77,350, dated April 28, 1868.

IMPROVEMENT IN SLED-KNEES.

The Schedule referred to in these Letters Patent and making part of the same.

TO ALL WHOM IT MAY CONCERN:

Be it known that I, JOHN W. BLAKE, of Jefferson, in the county of Jefferson, and State of Wisconsin, have invented a new and useful "Sled-Knee" for sleighs or sleds; and I do hereby declare that the following is a full and exact description thereof, reference being had to the accompanying drawing, making part of this specification, in which—

Figure 1 is the section of the sled-knee complete.

Figure 2 is a section showing lower shoulder and extension of the upright.

Figure 3 is a section of the upright, with a gas-pipe around it; and

Figure 4 is the side elevation of the plate D and the runner.

The nature of my invention consists in a metallic sled-knee, consisting of an upright and a brace, so combined with the foot and beam-plates as to form a perfect device to securely bind and hold together the runner, beam, rave, and bolster-block, as will be hereinafter fully explained.

To enable others skilled in the art to which my invention appertains to make and use said invention, I will proceed to describe its construction and operation.

A is an inclined upright, provided with a shoulder, A', its extension, a, passing through and beyond plate E, and shaped into a screw-bolt.

B is a brace, welded, or secured in any other way, to the upright, A, at a point just above the foot-plate D, and bent at the plate E, its extension, b, passing through and beyond said plate, and shaped also into a screw-bolt, both extensions, a and b, being so bent above the plate E as to form right angles with its upper or fitting-face.

D is a foot-plate, provided with flanges d d, to enclose the runner R, and counteract a lateral thrust, and is provided with holes O O, for the bolts to secure it to the runner. It may be cast around the foot of the upright, A, or may be made separately, and set on the upright, A, in which cases the upright is provided with another shoulder, a', as on fig. 2, and extends down through the plate and into the runner, being shaped into a screw-bolt to receive the nut r, countersunk in the runner R, and being bent so as to have this downward extension, x, at right angles with the lower or fitting-face of the plate D.

E is a beam-plate, cast around the upright, A, at its shoulder A', and around brace B at its bend, or may be made separately, and set loosely on the same.

Instead of making the upright, A, thicker between the plates D and E, it may be made of the same thickness all through, as on fig. 3, and passed through a sleeve, F, of a gas-pipe or steam-pipe shape, fitting between the plates D and E, and forming shoulders for the same to rest upon or abut to. More braces, B, can be used with the upright, A, if it is necessary or desirable. Beam G, rave H, and bolster-block I, are provided with holes, for the screw-bolted extensions, a and b, to pass through and receive nuts N N.

It is seen from the above that the sled-knee described, made of metal, and arranged in the manner shown, forms a perfect bending-device to secure and hold together the runner, beam, rave, and bolster of a sled, being at the same time durable and cheap.

What I claim as my invention, and desire to secure by Letters Patent, is—

The metallic sled-knee, consisting of the upright, A, and brace or braces B, with their extensions, a, b, and x, each made and arranged as described, and combined with plates D and E, in the manner herein shown and specified, the whole arranged and operating as and for the purposes set forth.

JOHN W. BLAKE.
